Primary Examiner — Richard A Edgar*Assistant Examiner* — Carolyn W Davis*(74) Attorney, Agent, or Firm* — NIXON & VANDERHYE P.C.(57) **CLAIM**

The ornamental design for an air purifier, as shown and described.

DESCRIPTION

FIG. 1 is a right, top, front perspective view of an air purifier in accordance with our new design;

FIG. 2 is a left, top, rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines shown in the figures depict portions of the air purifier that form no part of the claimed design.

1 Claim, 8 Drawing Sheets(56)
